UNITED STATES PATENT OFFICE.

ELMORE E. ROSE, OF SPRINGFIELD, MASSACHUSETTS.

BIT-BRACE FASTENING.

SPECIFICATION forming part of Letters Patent No. 275,860, dated April 17, 1883.

Application filed August 11, 1882. (No model.)

To all whom it may concern:

Be it known that I, ELMORE E. ROSE, of Springfield, in the county of Hampden and State of Massachusetts, have invented a new 5 and useful Improvement in Bit-Brace Fastenings, of which the following is a specification and description.

The object of my invention is to provide a fastening for bit-braces and breast-drills in 10 which to secure the drill or boring-bit, whereby the drill or boring-bit will be securely held during the operation of boring or drilling; and I accomplish this by the mechanism substantially as hereinafter described, and illustrated 15 in the accompanying drawings, in which—

Figure I is a side view of a breast-drill provided with my improved fastening. Fig. II is a side view of my improved fastening as applied to a bit-stock. Fig. III is a longitudinal 20 section of the fastening at line B of Fig. II. Fig. IV is an end view of the fastening. Fig. V is a perspective view of the jaws, jaw-stem, and the block which holds and actuates the jaws. Fig. VI is a perspective view of the 25 jaw-stem to which the jaws are secured. Fig. VII is a perspective view of the threaded block which is inserted into the jaw-stem and engages with the interior thread of the operating-sleeve, and Fig. VIII is a perspective 30 view of one of the springs which operate to open the jaws of the fastening.

In the drawings, 2 represents the shank of a bit-brace or drill-holder, to which the fastening is secured. 1 represents the socket, which 35 is hollow, and through which is made a mortise, 18. This socket 1 is permanently secured to the shank 2 by being made solid therewith or by being brazed thereto, and is provided with a sleeve, 3, having an interior screw-thread 40 made therein nearly or quite its whole length. The jaws 11 are each provided with a recess, 10, made on the inside of the jaw at a little distance from the inner end of each, which recess engages on a laterally-projecting lip, 9, of corresponding form, made on each side at the end of the jaw-stem 8, and two narrow cuts or slots, 13, are made in the jaw-stem, one on each side of and close to the shank, into each of which is secured a flat spring, 12, preferably by 45 setting the metal of the jaw-stem against the spring, so that each spring will be held firmly

in its slot in the jaw-stem, with its free end bearing against the outer face of the jaw at the inner end, as shown clearly in Figs. III and V, the inner end of the jaw being preferably beveled for the bearing of the spring against it, as shown at 15 in Fig. V. The outer face of each jaw, at 17, is inclined inward near its outer end and for a short distance from the end with reference to the remainder 55 of its length, as shown in Figs. III and V, and this outer face of each jaw is forced outward against the end of the opening 16 in the socket by the inward pressure of each spring 12 against its jaw behind the lip 9. A block, 6, having 60 a screw-thread made on each end to engage with the screw-thread on the interior of the sleeve 3, is fitted to and inserted in a mortise, 14, made through the enlarged part of the jaw-stem, and an annular groove, 5, is made around 65 the socket 1, inside the sleeve 3.

To put the parts together the jaws 11 are placed one on each side the shank 8, with the lips 9 in the recesses 10 on the inside of the jaws, and with the free end of each spring 12 70 bearing on the outer face of the jaw or on the beveled recess 15 at the inner end of the jaw, and the jaw-stem is then inserted into the socket 1 at the open end, with the mortise 14 through said jaw-stem coinciding with the 75 mortise 18 through the socket. The threaded block 6 is then inserted into the mortise 14 through the mortise 18 in the socket into its position shown in Fig. III, and the sleeve 3, which, before the block 6 was inserted, was 80 moved back as far as possible upon the shank of the bit-stock, is then turned forward and screwed onto the block 6, with the forward end of the sleeve against the shoulder 20, and a screw, 4, is then turned into a threaded hole 85 made in the sleeve, with the inner end of the screw in the annular groove 5, which holds the sleeve in its place on the socket. As the sleeve 90 3 is turned in one direction the block 6, jaw-stem, and jaws are moved forward, and as the springs 12 press inward against the inner ends of the jaws their outer ends are opened and cause the inclined outer side of each to ride against the end of the opening in the socket at the end. If the sleeve be turned in the other 95 direction, the block 6 and jaw-stem are moved backward, drawing the jaws in again, and as 100

the inclined back sides of the jaws ride against the ends of the opening in the end of the socket the jaws are forced together, firmly gripping the shank of a bit or a drill, if placed between 5 the jaws, so that the bit or drill will be firmly held in the jaws while boring with the brace.

It is evident that this device may be secured to the shank of any ordinary drill-stock as well as that of a bit-brace without departing 10 from the invention in the least.

The opening in the end of the socket is made of the proper width to just receive the jaws in the direction of their thickness, so that when 15 the jaws are in place in the socket they just fit the opening as to their thickness, but so as to slide freely therein, with the inclines on the jaws riding against the ends of the opening in said socket.

Having thus described my invention, what I 20 claim as new, is—

1. The combination, in an improved bit-brace fastening, of the mortised jaw-stem 8, the threaded block 6, the recessed jaws 11, inclined

on their outer edges, the springs 12, and the socket 1, all substantially as described. 25

2. The combination of a socket to contain the jaw-stem and jaws, a sleeve provided with an internal screw-thread, fitted and secured to said socket to revolve thereon, a jaw-stem provided at one end with a shank, with projecting 30 lips on its end, and with a mortise or slot made through said jaw-stem at the other end, two jaws having on the inside of each, near its inner end, a recess to receive the lips on the end of the shank, and an incline on the outside of 35 each jaw, near its outer end, to ride against the end of the opening in the socket, two springs secured in said jaw-stem, with their free ends pressing inward against the inner ends of the jaws, and a block fitted and inserted into the 40 slot or mortise through said jaw-stem, substantially as described.

ELMORE E. ROSE.
